UNITED STATES PATENT OFFICE.

GEORGE L. WAITT, OF BUFFALO, NEW YORK.

COTTER.

1,092,876.

Specification of Letters Patent. Patented Apr. 14, 1914.

Application filed August 25, 1913. Serial No. 786,586.

To all whom it may concern:

Be it known that I, GEORGE L. WAITT, a citizen of the United States, residing at Buffalo, in the county of Erie and State of New York, have invented new and useful Improvements in Cotters, of which the following is a specification.

This invention relates to a cotter or key for holding a bolt or the like in an opening 10 in which the same has been placed.

It is the object of this invention to produce a strong, durable and efficient cotter from sheet metal at low cost and of such a construction that the same is securely held in 15 the bolt through which it passes and also is held against rattling.

In the accompanying drawings: Figure 1 is a vertical section in part of a bolt provided with my improved cotter. Fig. 2 is a transverse section of the same taken in line 20 2-2, Fig. 1. Fig. 3 is a plan view of a blank from which the cotter embodying my invention is constructed. Fig. 4 is a perspective view of the cotter in its completed 25 form. Fig. 5 is a perspective view of the cotter showing the condition of the same ready for use.

Similar characters of reference indicate corresponding parts throughout the several 30 views.

In the drawings my improved cotter is shown applied to an ordinary coupling bolt which has a cylindrical shank or body 1 adapted to pass through a body and provided 35 at one end with a head 2 adapted to bear against one side of said body and provided at its opposite end with a transverse opening 3 which is adapted to receive my improved cotter. This cotter is preferably 40 constructed of a flat plate 4 of sheet metal preferably of oblong form and provided near its opposite ends with transverse cleavages 5, 6, which preferably extend transversely 45 inward partway from one of the longitudinal edges of the plate and form transverse stop lugs 7, 8 at opposite ends of the plate. One of these cleavages, for instance 5, is constructed by simply slitting the metal and thereby leaving the inner transverse edge 9 50 of the adjacent stop lug 7 perpendicular relative to the length of the cotter. The other cleavage 6 is however formed by removing some of the stock of the plate and producing a beveled or inclined face 10 on 55 the inner transverse edge of the other stop

lug 8 and tapering the same laterally, as shown in Fig. 3.

In manufacturing and marketing this cotter the same is made with the stop lug 7 bent laterally at right angles to the body of 60 the plate but the other lug 8 is left unbent and remaining in the same plane as the body of the plate, as shown in Fig. 5. In this condition of the cotter the same may be passed with its unbent end through the 65 opening in the coupling bolt until the rear stop lug 7 bears with its inner transverse edge 9 against the adjacent outer part of the bolt. The other stop lug 8 is now bent laterally at right angles or nearly so to the body 70 of the plate, thereby locking the cotter in the bolt and preventing the same from being withdrawn therefrom. Upon bending the stapling 8 laterally its inner beveled or inclined edge or face 10 engages the edge of 75 the adjacent end of the bolt opening with a wedging action, as shown in Fig. 2, thereby tightening the cotter in the bolt and preventing the same from rattling. The inclined face 10 of the stop lug 8 is preferably 80 of such extent that the same will engage the adjacent edge of the bolt opening notwithstanding that there may be slight variations in the size or diameter of the shank or body of the bolt or similar article which receives 85 the cotter.

I claim as my invention:

1. A cotter constructed of a plate which is provided with transverse cleavages forming two stop lugs at opposite ends of the plate 90 which are bendable laterally for confining the cotter in the opening of a bolt or the like, the inner transverse edge of one of said lugs being beveled so that said lug tapers laterally.

2. A cotter constructed of a plate which is 95 provided with transverse cleavages forming two stop lugs at opposite ends of the plate which are bendable laterally for confining the cotter in the opening of a bolt or the like, the inner transverse edge of one of said 100 lugs being beveled so that said lug tapers laterally while the inner transverse edge of the other lug is perpendicular relative to the length of said plate.

Witness my hand this 20th day of August, 105 1913.

GEORGE L. WAITT.
